UNITED STATES PATENT OFFICE.

ELTON FRANKLIN, OF JEFFERSON CITY, MISSOURI.

ARMORED VEHICLE.

1,283,405.

Specification of Letters Patent. Patented Oct. 29, 1918.

Application filed February 7, 1918. Serial No. 215,812.

To all whom it may concern:

Be it known that I, ELTON FRANKLIN, a citizen of the United States, residing at Jefferson City, in the county of Cole and State of Missouri, have invented certain new and useful Improvements in Armored Vehicles, of which the following is a specification.

This invention relates to new and useful improvements in armored vehicles, and the primary object of the invention is to provide a movable car, that is armored, and which carries a number of guns so that the vehicle is adapted to attack an enemy in position, with the gun crew of the vehicle fully protected.

Another object of the invention is to provide an armored vehicle of this character, which is provided with a peculiarly shaped protective body portion, which contains a plurality of guns projecting through ports in the sides thereof, and said body is mounted upon a supporting frame, which has forward and rear trucks, the whole vehicle being itself propelled, so that it may be advanced rapidly, and the peculiar shape of the armored body affording a maximum protection for the crew contained therein.

A further object of the invention is to provide a device of this character which is provided at opposite ends thereof with wire cutters, so that the vehicle may lead an advance through barbed wire entanglements as the force of the vehicle behind the wire cutter will sever the entanglements, and permit the infantry to pass therethrough with little trouble. This type of vehicle is steered at either end, so that it may be easily propelled in either direction. The vehicle is preferably driven by a gasolene engine, and the tank is disposed longitudinally within the body portion.

Another object of the invention is to provide a device of this character which is easily and simply constructed, inexpensive to manufacture, and one which will be very efficient in operation.

With these and numerous other objects in view, my invention consists in the novel features of construction, combination, and arrangement of parts, which will be herein referred to and more particularly pointed out in the specification and claims.

In the accompanying drawings:

Figure 1 is a side elevation of the armored vehicle;

Fig. 2 is a top plan view of the same,

Fig. 3 is a plan view of the supporting frame with the body removed, and

Fig. 4 is a horizontal longitudinal section through the upper portion of the body.

In describing my invention, I shall refer to the drawings in which similar reference characters designate corresponding parts throughout the several views.

My new and improved armored vehicle, comprises a metallic body portion 1, which is formed substantially cigar shaped, having an enlarged center portion, and converging opposite ends. The opposite sides of the body 1, are provided with a plurality of gun ports 2 that extend longitudinally along the same, through which the guns 3 are adapted to project. At one end of the body 1 is a hinged door 4, which permits access and egress from the interior of the body. The body 1 is formed of metal or other plate, that is of sufficient thickness to stand the ordinary gun fire, to which armored vehicles of this character are subjected, and this armor, is not heavy enough to materially effect the movability of the completed vehicle.

The body 1 is mounted upon a supporting frame designated broadly by the numeral 5, which is formed of a pair of channel members 6 and 7, which have connected main central portions 8, and outwardly extending end portions 9. The extremities of the channel members 6 and 7, are connected and securely mounted thereon adjacent the extreme points of the same, are supplemental supporting brackets 10 at opposite ends of the frame, which have their upper portions secured to the body 1 adjacent the extremities thereof. This type of supplemental support, is clearly shown in Fig. 1 of the drawings.

The body is primarily supported on the frame 5, at the center portion thereof as clearly shown in Fig. 1 of the drawings and disposed within the body 1, at said point, is the propelling means, the type illustrated in the accompanying drawings comprising a gas engine 11 of the conventional type, which is provided with a fuel tank 12 extending longitudinally within the body. This fuel tank forms a raised portion, that likewise forms a seat for the members of the gun crew and operators that are stationed within the vehicle.

Mounted beneath the enlarged portions 9 at the opposite ends of the channel bars 6 and 7 of the supporting frame, are front

- and rear trucks 13 and 14, which carry axles 16 upon which are mounted wheels 17. Securing mechanism 18 of the conventional type, is connected with the axles and wheels, 5 and is operable by steering wheels 19 disposed within the body 1 adjacent opposite ends thereof. This permits the vehicle to be steered from either end thereof accordingly to the direction in which it travels.
- 10 The trucks, are provided with the usual type of springs 20, which overcome to a large extent, the excessive jar incident to the operation of the vehicle over very rough ground.
- 15 At the opposite ends of the vehicle, I provide wire cutters 21, which are secured to the brackets 10 as clearly shown at 22, intermediate the ends of said wire cutters by a projecting portion, and also secured to 20 the extremities of the frame 5, as clearly shown at 23. The wire cutters 21 project upwardly from the connection 22, and are curved around the end of the body of the vehicle, while the portion extending below 25 the frame 5, extends forwardly to a point adjacent the ground, where at its lower extremity it is provided with a pair of diverging cutters 24 the purpose of which is obvious. These wire cutters are used for cutting a passage through barbed wire entanglements, when the armored vehicle is used to lead an infantry attack.
- 30 This type of armored vehicle forms a very efficient device of this character, which 35 affords the maximum protection for the crew when operating the same in battle. The peculiar shape of the protective body, affords the best protection possible for the vehicle proper, and the guns mounted there- 40 on permit an intense offensive to be carried on during the operation of the vehicle. The guns have a limited movement through the ports 2 in the sides of the vehicle body, so as to increase their range. The construc- 45 tion for supporting the body, is reduced to a minimum, and the frame 5 and trucks de- pending therefrom form a very efficient supporting means for this type of vehicle. The engine is inclosed within the body 1, as 50 are the steering wheels, whereby the vehicle is guided. The long tank that is disposed

centrally within the body, permits the vehicle to carry a large amount of fuel, as well as affording a rest for the crew therein. Attention is particularly directed to 55 the wire cutting means employed at the opposite ends of the vehicle, that permits the same to advance under certain adverse conditions.

From the above description taken in connection with the accompanying drawings, it is thought that a clear and comprehensive understanding of the construction, operation, and advantages of my invention may be had, and while I have shown and described the device as embodying a specific structure, I desire that it be understood that such changes may be made in said structure as do not depart from the spirit and scope 60 of the invention as claimed.

Having fully described my invention, what I claim is new, and desire to secure by Letters Patent, is:

1. In a vehicle of the class described, a frame having tapered ends and its intermediate portion constricted, a body comprising a shell having tapered ends mounted on said frame, wheels mounted on the frame, a prime mover in the body connected to certain of the wheels, and wire cutting means 75 fixedly mounted on the opposite ends of the frame projecting beyond the adjacent side portions of the body.

2. In a vehicle of the character described, a frame having tapered ends and its intermediate portion constricted, a body comprising a shell having tapered ends mounted on said frame, wheels mounted on the frame, a prime mover in the body connected to certain of the wheels, substantially V- 80 shaped horizontally disposed wire cutting elements fixedly secured to the opposite ends of the frame and extending beyond the adjacent side portions of said body, and vertically disposed curved wire cutting elements 85 secured to the frame and extending upwardly into proximity to portions of said body.

In testimony whereof, I affix my signature hereto.

ELTON FRANKLIN.
